UNITED STATES PATENT OFFICE.

RICHARD ZIESING, OF CLEVELAND, OHIO.

FURNACE.

1,279,486.

Specification of Letters Patent. Patented Sept. 17, 1918.

Application filed May 25, 1916. Serial No. 99,882.

To all whom it may concern:

Be it known that I, RICHARD ZIESING, a citizen of the United States, and a resident of Cleveland, county of Cuyahoga, and State of Ohio, have invented a new and useful Improvement in Furnaces, of which the following is a specification, the principle of the invention being herein explained and the best mode in which I have contemplated applying that principle, so as to distinguish it from other inventions.

The subject of the present invention is a furnace designed for the distillation of zinc, the features forming the subject matter of the invention relating to the construction of the side walls of the furnace and also of the arches, and the object of the invention being to secure a more intimate mixture between the products of combustion and the auxiliary air that is supplied at different points along the length of the furnace, a more efficient combustion of these gases and an even distribution of the heat throughout the various parts of the furnace. Another object of the invention is to secure parallelism between the retorts after the furnace has taken its first "set" in order that all of the retorts may be heated and effected equally by the products of combustion, which is not secured in furnaces of the present type. A still further object is to reduce the wear on the furnace, thus securing longer life, and to increase the yield of metal. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Figure 1 is a horizontal section through my improved furnace, Fig. 2 is a vertical section on the line 2—2, in Fig. 1; and Fig. 3 is a vertical section on the line 3—3, Fig. 1.

From the drawings the general construction of the furnace will be readily seen, and it will be obvious that in general it follows the present types of construction for zinc furnaces in which there is a combustion chamber 1 disposed horizontally and of considerable length, through which the products

of combustion pass longitudinally, and in which are arranged a series of retorts 2, the retorts being preferably in series of four as shown, and being inclined slightly to the horizontal. On either side of the combustion chamber are tracks 4 which are adapted to receive the cars into which the distilled zinc is discharged, the waste products from the retorts being cleaned out and discharged into the chutes 5 which empty into cars 6 on a track 7 disposed in a chamber below the combustion chamber. At intervals along the length of the combustion chamber are auxiliary air supply conduits 8 which discharge laterally through the nozzles 9 as shown in Fig. 2. These air supply conduits 8 furnish additional air to the combustible gases passing through the chamber, and maintain the combustion throughout the entire length of the furnace. The furnace as described above is similar to those now in general use and is distinguished therefrom and bettered by means of the features now to be explained.

The path of the burning gases and products of combustion is shown by the arrows in Fig. 1, and it will be seen that at no point do the burning gases strike the inner wall. The atmosphere along this wall, consisting largely of burnt gases will be heated by radiation to approximately the same temperature as the front of the furnace chamber.

It has been found that one difficulty with the present type of furnace is that the rush of auxiliary air across the path of travel of the combustible gases causes the latter to eddy to the back of the furnace, and at points opposite to the supply conduits 8, this rear furnace wall or lining is burned away very fast. Furthermore, this unequal heating causes the retorts to wear away very fast producing numerous breaks and letting the ore and slag fall down over the other retorts. This ore is practically a total loss in addition to the loss of the broken retorts.

This rapid and unequal deterioration of the furnace lining is not only expensive, but also, the cause of it, which is the burning of the gas at certain points along the rear wall, prevents an even heating of the outer side of the combustion chamber and thus the outer ends of the retorts do not receive the same temperature as the inner ends. It has been found that the zinc at the inner ends of the retorts 2 will be distilled off six

100

105

110

or, more hours sooner than the zinc at the outer ends. Thus, if it is possible to maintain an even temperature throughout the furnace, the life of the retorts and of the 5 furnace lining can be increased very greatly, and also the recovery since less ore is lost through broken retorts and since less metal deposits in the slag at the mouth of the retort.

- 10 I have found that by disposing baffles or partitions 10 in the furnace opposite to each of the air supply conduits 9, that this burning of the rear wall can be avoided, and also that a better combustion can be secured and 15 an even temperature maintained over the entire surface of each retort. By thus separating the combustion chamber into a number of recesses or chambers, it is possible to localize any deterioration that may occur, 20 and this saves enormously in the cost of replacement of the inner walls.

The construction of the inner wall is best shown in Fig. 2, the wall consisting of an inner core 11, provided with shoulders 12 at 25 its base, upon which are supported horizontally disposed refractory members, such as fire-brick 13, mounted upon which are vertically disposed brick 14, thus forming narrow shelves or shoulders upon which the 30 inner ends of the retorts 2 may be supported. Upon the top of the bricks 14, other bricks are placed horizontally to form the support for the next retort. Preferably five layers of retorts are disposed in each of the 35 recesses between the partitions 10, and the bricks 13 and 14 are so proportioned that between each two adjacent retorts there is a very narrow acute angle formed. It will also be seen that the top of the furnace is 40 formed of a member 15 having a flat bottom which is originally placed at an acute angle with the top of the upper retort.

It is known that after the first use of such a furnace, the bricks of the inner wall 45 shrink to some extent, and take a permanent set which is but slightly changed during the remainder of the operation of the furnace. By positioning the retorts at slight angles to each other and by forming the top of the 50 furnace in the manner indicated in Fig. 2, it is possible to secure approximately parallelism between the retorts and the roof of the furnace after this first shrinking has occurred. From that time on there is approxi- 55 mately an equal distance between each two adjacent retorts and between the upper retort and the roof of the furnace, and thus all of the retorts are effected equally by the products of combustion and each will operate 60 equally well upon the zinc which is treated therein, whereas before, it was practically impossible to secure an even temperature in the different parts of the furnace. It will be seen that the outer faces of the 65 bricks 14 are so formed that when the lining

settles, the inner ends of the retorts 2 will abut flatly against them, the successive bricks 14 being beveled at different angles to permit of this desired settling.

Other modes of applying the principle 70 of my invention may be employed instead of the one explained, change being made as regards the mechanism herein disclosed, provided the means stated by any of the following claims or the equivalent of such stated 75 means be employed.

I therefore particularly point out and distinctly claim as my invention:—

1. In a furnace, the combination of a 80 horizontal combustion chamber, means adapted to pass combustible mixtures longitudinally therethrough, a plurality of retorts arranged transversely therein, a plurality of air supply conduits arranged to discharge laterally into said chamber at intervals along 85 the same, and means in said chamber for directing the gases passing through said chamber toward such air conduits.

2. In a furnace, the combination of a horizontal combustion chamber, means adapted 90 to pass combustible mixtures longitudinally therethrough, a plurality of retorts arranged transversely therein, a plurality of air supply conduits arranged to discharge laterally into said chamber at intervals along the 95 same, and a series of baffles arranged in said chamber and terminating opposite to said air conduits and adapted to direct the gases passing through said chamber toward such air conduits.

3. In a furnace, the combination of a horizontal combustion chamber, means adapted 100 to pass combustible mixtures longitudinally therethrough, a plurality of retorts arranged transversely therein, a plurality of air supply conduits disposed in one side wall of 105 said chamber and arranged to discharge laterally thereinto, and a series of baffle plates extending laterally from the opposite side wall of said chamber and terminating opposite to said air conduits.

4. In a furnace the combination of a combustion chamber and refractory supports on either side of said chamber adapted to receive retorts thereon, said supports being 110 proportioned and initially installed to bring such retorts into parallelism with their ends abutting flatly against the supports upon settling.

5. In a furnace the combination of a combustion chamber and refractory supports on either side of said chamber adapted to receive retorts thereon, said supports being proportioned and initially installed to bring such retorts into equidistant parallelism with 115 their ends abutting flatly against the face of the supports upon settling.

6. In a furnace the combination of a combustion chamber, refractory supports on either side of said chamber adapted to re- 120 125 130

ceive retorts thereon, and a roof mounted upon said supports, said supports being proportioned to bring such retorts and said roof into equidistant parallelism upon settling.

5 7. In a furnace the combination of a combustion chamber, supports along one side thereof adapted to receive one end of a series of retorts and refractory supports along the opposite side thereof adapted to receive the 10 other end of such retorts, said refractory supports being proportioned and initially installed to bring such retorts into equidistant parallelism with the ends of the retorts abutting flatly against the faces of the supports upon settling.

15 8. In a furnace, the combination of a combustion chamber, supports along one side thereof adapted to receive one end of a series of retorts, refractory supports along the 20 opposite side thereof adapted to receive the other end of such retorts, and a flat arch roof mounted upon said supports, said supports and roof being proportioned to bring

such retorts and roof into equidistant parallelism upon settling.

9. In a furnace, the combination of a combustion chamber, supports along one side thereof adapted to receive the outer ends of a series of retorts, and refractory supports along the opposite side thereof 30 adapted to receive the inner ends of said retorts, said refractory supports being proportioned and initially installed to support said retorts in an unparallel relation to each other with the inner ends thereof at an acute 35 angle to the faces of the said refractory supports, to thereby bring the retorts into equidistant parallelism with the inner ends of the retorts abutting flatly against the faces of the supports.

40 Signed by me this 20th day of May, 1916.

RICHARD ZIESING.
